SPARK-PLUG.

1,270,437.

Specification of Letters Patent. Patented June 25, 1918.

Application filed November 21, 1913, Serial No. 802,193. Renewed November 16, 1917. Serial No. 202,426.

To all whom it may concern:

Be it known that I, WALTER REPPIN, a citizen of the United States, residing in the city of Newark, in the county of Essex and State of New Jersey, have invented certain new and useful Improvements in Spark-Plugs, of which the following is a full, clear, and exact description, such as will enable others skilled in the art to which it pertains to make, construct, and use the same, reference being had to the accompanying drawings, and to numerals of reference marked thereon, forming a part of this specification.

This invention relates to improvements in electric sparking devices, particularly spark plugs for use for igniting the explosive gases in the cylinders in internal combustion engines, and the said invention consists in the construction, combination and arrangements of parts hereinafter shown and described.

The object of this invention is to prevent short circuiting of spark plugs, by employing a series of electrodes insulated in a manner to form a series of gaps for the passage of the electrical spark. These electrodes may be readily mounted upon an insulating core or within a suitable recess formed in the end of the insulating core.

It is well known that the heat value of the current is inversely proportional to the resistance of the circuit, and by introducing electrodes in series, the resistance of the circuit is much less than the resistance of a gap, whose combined length would be equal to the sum of all the gaps, and by thus having lowered the resistance of the circuit, a greater amount of current is utilized in producing a spark, and for this reason, the spark would be hotter.

Heretofore, it has been customary to employ a single spark gap, or a number of spark gaps, but in such a manner that if one of these gaps should become short circuited, either by oil, carbon, or otherwise, there would be no spark at any of the gaps, whereas in the construction of my plug, if one or more electrodes should become short circuited, the remaining gaps would produce a more intense spark because of the lower resistance in the circuit.

The electrodes which I employ are preferably in the nature of open rings, which facilitate the ready mounting or assembling thereof on the insulating core, and although

I do not wish to be limited to the use of open rings, since experience has demonstrated that closed rings in some instances may be desirable, I find that in the use of open rings, as shown in the accompanying drawings, where the plug is exposed to the action of oil, the same form a ready means for permitting any surplus of oil which might have a tendency to adhere to the plug to be discharged therefrom.

In the preferred form of my invention, I have shown the metallic base which is screwed into the motor cylinder, provided with an annular recess or cavity extending over the series of electrodes in such a manner as to confine the sparks and intensify the same, by virtue of the metallic shell inclosing the sparks, thus producing a solid flame, and also to prevent as far as possible, the ingress of oil upon the central core and the series of electrodes.

It is also known that the accumulation of unconsumed oil in the cylinder is the cause of carbonization, and if for any reason the plug becomes short-circuited, this oil cannot be consumed, and quickly carbonizes. By the employment of a plug made in accordance with my invention, which prevents mis-firing, by reason of the intensity of the series of sparks produced under any existing conditions in the cylinder, all the lubricating oil in the cylinder and on the spark plug will be burnt and no carbonization will take place.

Another advantage of this spark plug resides in the fact that due to the intensity of the spark, I am enabled to ignite a weaker mixture and thus get increased efficiency from the motor.

In the accompanying drawings, Figure 1 represents a central vertical section of a spark plug embodying my invention in its preferred form.

Fig. 2 represents a side elevation of the centrally bored insulating core removed from the plug, provided with a central electrode and a plurality of electrodes.

Fig. 3 represents a similar view, partly in section, of a modified form of the insulating core.

Figs. 4 and 6 represents plan views of the preferred forms of electrodes to be used in connection with my improved device.

Fig. 5 represents a plan view of a pre-

ferred form of washer to be used in connection with my improved device; and

5 Figs. 7 and 8 represent fragmentary views of modified forms of insulating cores, provided with a plurality of electrodes.

Similar numerals of reference indicate corresponding parts throughout the specification and drawings.

So far as the general construction of the 10 plug is concerned, it may be of any desired form or structure.

In the present instance, it is illustrated as comprising a centrally bored insulating core 1, which may be of mica, porcelain, or other 15 suitable material, surrounded by a chambered casing 2 which is externally threaded, as at 3, for connection with the apparatus or engine in which it is to be used, and internally threaded as at 4, for the reception 20 of an exteriorly threaded nut 5, by means of which the insulating body or core and the casing 2 are firmly secured together.

A suitable washer or packing 6 may be used between the shoulder 7 of the insulating core 1 and the shoulder 8 of the casing 2. Extending through the insulating body 1 is the electrode 9, which is provided with an enlarged head 10, between which and the insulating body is located a suitable washer 11, provided with two diametrically-oppositely arranged projections 12, as clearly illustrated in Fig. 5 of the drawings, and which electrode is secured in position by means of the usual nuts 13 and 14, turned on 25 the threaded end of the electrode and between which nuts and the insulating body, is also located a suitable washer 15.

The insulating body 1 is provided with a reduced portion 16, projecting an appreciable distance inside the end of the chambered casing 2, having formed thereon, a plurality of preferably parallel grooves, in this case, four in number, although any convenient number may be employed, into which are 40 sprung the electrodes 17, preferably made of ordinary steel wire, the first three of which are in the nature of open rings, as illustrated in Fig. 4 of the drawings, and the last electrode is preferably made with a 45 projecting end 18, as illustrated in Fig. 6 of the drawings, designed to be grounded in the chambered casing 2, as clearly indicated in Fig. 1 of the drawings.

It will thus be seen that by mounting the 50 washer 11 and a number of electrodes 17 on the insulating core, said electrodes being insulated from each other, a series of small uniform gaps from the central electrode to the casing 2 are formed. By the employment of open rings, the ready mounting or assembling of the electrodes on the insulating core is greatly facilitated, and furthermore, the use of open rings, particularly where the plug is exposed to the action of 55 oil, form a ready means for permitting any

surplus of oil which might have a tendency to adhere to the plug, to be discharged therefrom.

The chambered casing 2 after the insulating core has been secured therein, forms an 70 annular cavity 19, surrounding the electrodes in such a manner as to confine the sparks and intensify the same, by virtue of the chambered casing inclosing the sparks, thus producing a solid flame, and also preventing 75 as far as possible, the ingress of oil upon the central core and electrodes.

In Fig. 3 of the drawings, I have shown the insulating core provided with preferably a tapered recess provided with a series of 80 grooves, into which the electrodes, in the nature of open rings, can be conveniently sprung. In this case, the first ring would be provided with a downwardly extending offset designed to be grounded on the cas- 85 ing 2.

In the modified form illustrated in Fig. 7 of the drawings, I have shown the electrodes in the nature of steel washers 20 properly insulated from the central electrode 9, by 90 means of washers 21 made from suitable insulating material, and in Fig. 8, another modified form, I have shown the electrodes in the form of a plurality of pins or studs 22, conveniently secured and arranged on 95 the outside of the insulating core, in any well known manner.

It will thus be seen that with a plug made in accordance with my invention, I am enabled, firstly, to get a more intense spark 100 because of the employment of a series of electrodes which are mounted upon the insulating core. Secondly, I am enabled to ignite weaker mixtures and thus get increased motor efficiency, because of the increased intensity of the spark. Thirdly, short circuiting is absolutely overcome, by arranging the electrodes in series and insulating them from each other, it being readily understood that if one spark gap should 110 be short-circuited, the resistance in the circuit would be immediately lowered, and the resulting sparks at the remaining gaps would only be intensified; and fourthly, in the construction of my plug, it becomes unnecessary to take the same apart for adjusting the gaps, since, if the metal is burned away by the action of the electrical current at one point of the rings, the sparks will 115 continue to jump at some other and less distant points of the rings, where the metal has not been burned away.

Experience has demonstrated that the organization above described is a highly efficient one, and while I have shown the preferred embodiment of my invention, I do not care to be limited to the exact structure shown and described, as minor variations thereof may be made by any one skilled in the art.

I claim:

1. A spark plug comprising an insulating body reduced at its lower end, a chambered casing surrounding the reduced portion of said body, a central electrode extending through said insulating body, a number of electrodes consisting of open rings secured to the reduced portion of the insulating body insulated from each other and from the central electrodes so as to form a series of gaps, all electrodes secured to the outside of the reduced portion of the insulating body having their sparking surfaces within the chamber of said casing.
- 10 2. A spark plug comprising an insulating body reduced at its lower end, a chambered casing surrounding the reduced portion of said body, a central electrode provided with an enlarged head extending through said in-

sulating body, a number of electrodes consisting of open rings secured to the reduced portion of the insulating body insulated from each other and from the central electrode so as to form a series of gaps, all electrodes secured to the outside of the reduced portion of the insulating body having their sparking surfaces within the chamber of said casing, said chambered casing surrounding said electrodes and inclosing the same, and a washer provided with projections interposed between said insulating body and the enlarged head of the central electrode.

This specification signed and witnessed this seventh day of November, 1913.
